CLAIM

The ornamental design for a portable electronic device, substantially as shown and described.

DESCRIPTION

FIG. 1 is a top front perspective view of our new design; FIG. 2 is a bottom front perspective view of the design of FIG. 1;

FIG. 3 is a front elevational view of the design of FIG. 1; FIG. 4 is a rear elevational view of the design of FIG. 1; FIG. 5 is a left side elevational view of the design of FIG. 1;

FIG. 6 is a right side elevational view of the design of FIG. 1;

FIG. 7 is a top view of the design of FIG. 1; and, FIG. 8 is a bottom view of the design of FIG. 1.

The broken lines shown in FIGS. 2 and 8 illustrate portions of the portable electronic device that form no part of the claimed design.
